GOLF BALL TEEING APPARATUS

Earl E. Williams, Augusta, Kans.

Original application February 18, 1948, Serial No. 9,169. Divided and this application March 29, 1949, Serial No. 84,101. In Great Britain June 28, 1948

4 Claims. (Cl. 273—33)

1

This invention relates to a game, and particularly to a golf game.

Still more particularly it relates to a mechanism for the positioning of a golf ball.

This application is a division of my co-pending application Serial No. 9,169, filed February 18, 1948, and issued as U. S. Patent 2,581,738.

The particular object of this invention is to provide an indoor golf game which will be highly realistic and in which it is possible substantially to duplicate tee conditions encountered on the ordinary golf links.

It is also an object of this invention to provide an automatic tee for use in connection with golf games or driving ranges.

It is a further object of this invention to provide a tee which holds a ball in a fixed position from which it can only be dislodged by a sharp blow.

A still further object of the invention is to provide a tee mechanism which not only delivers the ball to the driving platform but automatically positions the ball on the tee and holds the ball against accidental rolling off the tee.

These and other objects and advantages will become more apparent upon reference to the following description taken in connection with the accompanying drawings in which:

Figure 1 is a sectional view of the automatic tee according to this invention which spots the ball preparatory to the driving thereof; and

Figure 2 is a fragmentary sectional view of a tee when the ball carrying member starts its descent into the tube recess below the tee.

Referring to the drawings, the ball 11 is supported on a tee proper indicated at 15, which comprises a tubular nipple extension above the level of floor 16. The nipple 15 is supported on the hollow L piece 17 which is rigidly supported in a block 18.

Block 18 is pivotally mounted relative to the floor by a hollow shaft 19. This hollow shaft 19 communicates with the hollow interior of the L-shaped member 17 and therethrough with the nipple 15 by the passage 20.

Connected with the hollow interior of the shaft 19 as by conduit 21 is a source of vacuum, and the conduit 21 may include a throttle valve 21a if desired.

The passage 20 also communicates with a cylinder 22 having therein a piston 23 which is continuously urged toward the right by compressible means 24 such as a spring.

It will be apparent that when the ball 11 is resting against the open end of nipple 15 that the

2

vacuum established in the passage 20 will also be established within the cylinder 22 on the piston 23 to draw it leftwardly against the spring 24, allowing a switch 25 to close.

5 This switch is positioned at the extreme right end of the cylinder 22 and when the vacuum is broken in the cylinder 22 the switch is opened by the piston 23 when it is moved rightwardly by the spring 24.

10 Directly beneath the nipple 15 and in axial alignment therewith there is a tube 26 which has opening into the side thereof an arcuate conduit 27 which connects with a ball hopper 28 supported on and conveniently located above the floor 16 adjacent to ball position.

20 Slidably mounted within the tube 26 is a ball carrying member 29 including a golf ball seat and which member 29 has secured thereto a rack 30 on which runs the pinion 31 carried on the shaft of a reversible motor 32, said shaft being driven through an over-running clutch of any suitable construction. It will be apparent that driving the motor 32 in one direction will move the ball carrying member 29 upwardly, and driving the motor in the other direction will move said carrier downwardly.

25 Associated with the portion of the tube 26 adjacent its connection with the conduit 27 is an escapement for balls, which consists of a disc 33 and a pair of ball retaining pins 34 thereon movable in arcuate slots 35 in the conduit 27.

The disc 33 carries an arm 36 and this arm extends into the path of pin 37 carried by the ball carrier member 29 and projecting through a slot 38 in the tube 26.

30 It will be apparent that if the ball carrier member 29 is in an upper position the disc 33 will be moved counter-clockwise by a spring 39 so that the ball will roll against the right hand pin 34.

35 Thus, when the ball carrier member 29 is retracted downwardly to the position shown in Figure 1, the pin 37 will engage the arm 36 to rotate the disc 33 clockwise and thereby release the ball resting against the right hand pin 34.

40 This arrangement provides for the delivery of one ball at a time to the ball carrier member 29. When a ball has been delivered to the ball carrier member 29 and it is desired to place the ball on the tee, the ball carrier member 29 is actuated upwardly.

45 The operation is shown in more detail by reference to Figure 2. As the ball carrier member 29 moves upwardly the ball 11, and not the ball carrier member 29, contacts and L-shaped member 17 because of slot 41, referred to hereinaft-

er, and lifts it to the dot-dash position 40 in Figure 2.

In this Figure 2 the carrier 29 is shown to have progressed to a point where the L-shaped member 17 has fallen beneath the ball due to slot 41 in the side of the ball carrier member 29, so that when the ball carrier member 29 is retracted the ball will be deposited on the upper end of nipple 15 as shown in Figure 1.

For the purpose which will become more apparent hereinafter, the ball carrier 29 has a latch member 42 thereon adapted for being engaged by a latch member 43 to which is connected a retracting solenoid S. This retracting solenoid S associated with latch member 43 is connected in circuit with the switch 25 through a source of power, such as a battery, by leads 44.

As will be seen when there is a vacuum in the cylinder 22 the switch 25 is operated to energize the solenoid S and thus to retract the latch member 43 allowing the carrier 29 to move to the ball receiving position.

In operation the motor 32 is normally energized from a battery 45 through a switch 14 to run in a direction urging carrier member 29 downwardly. In order to drive the member 29 upwardly the motor 32 is reversed by pressing the switch 14. This reverses the direction of the motor 32 and raises the member to its uppermost position.

Thus, when switch 14 is released the motor 32 is reversed and moves the member 29 downwardly until the latch members 42 and 43 meet, at which time further movement of the member 29 is stopped.

Thereafter, when the latch 43 is withdrawn by energization of the solenoid S the member 29 continues its downward movement and comes to rest in the lowermost position shown in Figure 1.

Operation of the tee mechanism may be summarized as follows:

When a ball has been driven from the tee a new ball is spotted on the tee by pressing the switch 14 which causes the ball carrier to move upwardly to its uppermost position.

The switch 14 is then released and the carrier 29 moves downwardly leaving the ball on the nipple 15 and is halted by the latch 43.

Thereafter the closing of the end of the tee by a ball causes a vacuum to build up in the cylinder 22 which in turn brings about the retraction of the latch 43 and the movement of the carrier 29 to its lowermost position.

As the carrier 29 retracts pin 37 contacts arm 36 which in turn rotates disc 33 until the rightward pin 34 is withdrawn from conduit 27, thus freeing the path of the ball from obstruction allowing the ball to fall into the ball retaining pocket of the carrier 29, where it is in position to be elevated and placed on the nipple 15.

It will be understood that this invention is susceptible to modification in order to adapt it to different usages and conditions and accordingly, it is desired to comprehend such modifications within this invention as may fall within the scope of the appended claims.

I claim:

1. In a teeing device for golf balls, ball positioning means comprising a base at ground level having an opening therein, a pivotable block in said base, an L-shaped hollow shaft rigidly supported in said pivotable block; a tubular resilient nipple projecting at ground level and upstanding adjacent the end of said shaft and having its

interior in communication with the interior of said shaft; a conduit in said block serving to connect said shaft with a source of vacuum; a cylinder mounted in horizontal alignment with said hollow shaft; a piston in said cylinder; yieldable means continuously urging said piston in one direction; communication means between said cylinder and the conduit whereby vacuum while maintained urges the piston in the direction overcoming the force of the yieldable means; switch means actuated by said piston; a gear; a gear driven tubular member having a golf ball seat therein and vertically movable beneath and in axial alignment with said nipple and slotted at an upper wall portion thereof for receiving the L end of said hollow shaft; motor means for driving said gear to reciprocally move said tubular member in a vertical plane past said block at said opening in said base; latch means to halt said carrier in an upper position; means responsive to said switch actuated by said piston for withdrawing said latch; a hopper; a conduit extending from said hopper to immediately above the lowermost position of said tubular member; and escapement means operable by movement of said tubular member to permit balls to be fed singly from said conduit only when the tubular member and ball seat are in position to receive said ball.

2. In a teeing device for golf balls, ball positioning means comprising a single vertically disposed and movable tubular member having a longitudinal slot in an upper wall portion thereof, a golf ball seat in said member interposed between the ends of said slot, a horizontally extending member pivotally mounted for movement in a vertical plane and having a portion thereof including a golf tee extending into the path of said vertically movable tubular member at said slot, said tee comprising a nipple which is connected to a vacuum source, and means to reciprocate said tubular member in said vertical plane past said horizontally extending member whereby said horizontally extending member may be displaced by contact with a ball in the said seat of said tubular member by the vertical rise thereof and said ball is deposited on the said tee in the downward movement of said tubular member.

3. In a teeing device for golf balls, ball positioning means comprising a single vertically disposed and movable tubular member having a longitudinal slot in an upper wall portion thereof, a golf ball seat in said member interposed between the ends of said slot, a horizontally extending member pivotally mounted for movement in a vertical plane and having a portion thereof including a golf tee extending into the path of said vertically movable tubular member at said slot, said tee comprising a nipple which is connected to a vacuum source, and means including a motor, a rack and pinion on said tubular member connected to be driven by said motor and a switch for controlling the direction of rotation of said motor, said motor being selectively energized by said switch to reciprocate said tubular member in said vertical plane past said horizontally extending member whereby said horizontally extending member may be displaced by contact with a ball in the said seat of said tubular member by the vertical rise thereof and said ball is deposited on the said tee in the downward movement of said tubular member.

4. In a teeing device for golf balls, ball positioning means comprising a single vertically disposed and movable tubular member having a

longitudinal slot in an upper wall portion and a first latch member extending from an outer wall thereof, a golf ball seat in said member interposed between the ends of said slot, a base member having an opening therein for passage of said tubular member, a horizontally extending member pivotally mounted in said base member for movement in a vertical plane and having a portion thereof including a hollow golf tee extending into the path of said vertically movable tubular member at said slot, said horizontally extending member comprising vacuum means connected with said hollow tee, means to reciprocate said tubular member in said vertical plane past said horizontally extending member where-
by said horizontally extending member may be displaced by contact with a ball in the said seat of said tubular member by the vertical rise thereof and said ball is deposited on the said tee in the return movement of said tubular mem-
ber, a second latch member supported from said

5 base member adjacent the path of travel of said first latch member on said tubular member for holding said tubular member in its downward motion, and means including a switch and solenoid responsive to buildup of vacuum in said hollow tee for withdrawing said second latch and permitting continued downward movement of said tubular member.
